L. A. TRULL,
VULCANIZED BOOT AND SHOE,
APPLICATION FILED NOV. 19, 1919.

1,374,480.

Patented Apr. 12, 1921.

UNITED STATES PATENT OFFICE.

LYMAN A. TRULL, OF WILLIAMSPORT, PENNSYLVANIA, ASSIGNOR TO LYCOMING RUBBER COMPANY, A CORPORATION OF PENNSYLVANIA.

VULCANIZED BOOT AND SHOE.

1,374,480.

Specification of Letters Patent. Patented Apr. 12, 1921.

Application filed November 19, 1919. Serial No. 339,021.

To all whom it may concern:

Be it known that I, LYMAN A. TRULL, a citizen of the United States, and a resident of Williamsport, in the county of Lycoming and State of Pennsylvania, have invented 5 certain new and useful Improvements in Vulcanized Boots and Shoes, of which the following is a full, clear, and exact description.

10 This invention relates more particularly to rubber-soled shoes of the type having a canvas upper and an outer sole of rubber.

The invention has for its object to provide a shoe of the said type which closely resembles a Goodyear welt shoe, and in which the margin of the outer sole is, in effect, secured to the inner sole by permanent metallic or other fastening means which is entirely concealed.

20 The invention will be understood by reference to the accompanying drawings, in which:

Figure 1 is a perspective view of a shoe embodying the invention, parts being cut 25 away and laid back to disclose certain details of construction.

Fig. 2 is an enlarged sectional detail view illustrating the relative arrangement of the parts.

30 Fig. 3 is a perspective view of one of the metallic fasteners for securing the parts in place, and

Fig. 4 is a broken away perspective showing the toe portion of the shoe.

35 In manufacturing the shoe illustrated in the drawings, the inner sole 1, which may be made of fiber board, leather or other suitable material is first placed upon the bottom of the last. The upper 2 of canvas or other 40 suitable fabric is then shaped to the last and its margin 3 turned over and secured to the inner sole, preferably by tacks 4, the points of which are clenched to the inner sole by striking against the bottom of the last. It 45 is to be understood however that, if desired, stitches, cement, or other means may be employed instead of tacks to secure the overlasted margin of the upper to the inner sole.

The welt strip 5 of rubber composition is 50 next applied about the edge of the shoe, and is so disposed that its inner portion 6 lies upon the overlasted margin 3 of the upper, while its outer portion 7 protrudes beyond the upper, giving to the shoe the appearance and the advantages of a leather shoe of

the welt type. Preferably, the upper surface 8 of the protruding portion 7 of the welt strip is formed with transverse ridges 9 to simulate the indented stitching of a leather shoe. It will be noted that the portion of the strip which lies upon the folded margin 3 of the upper is reduced in thickness so as to provide a shoulder against which the upper rests at the line of fold of the said margin, and a second shoulder 60 lying against the edge of a fabric binder sheet 11. By this means the welt is so positioned with respect to the upper as to enhance the appearance of the shoe, and the said shoulders aid in resisting the strains upon the 70 projecting margin of the outer sole which tend to pull the latter loose from the insole.

After the welt strip has been applied, the space within its inner margin is filled with a suitable vulcanizable plastic composition 75 10 to level the bottom of the shoe.

The binder sheet 11 is next applied. This sheet is composed of fabric frictioned or otherwise coated on both sides with rubber. The binder sheet is employed to enable a strong vulcanized union to be formed between the rubber outer sole and the filler. The binder sheet in the present instance overlaps the tape-like extension of the welt strip which lies over the margin 3 of the 80 upper, and metallic fasteners 12 employed to secure the welt strip to the inner sole are driven through the binder sheet. Any other suitable fastening means may be employed 85 in place of the metallic fasteners. 90

The toe portion of a shoe is obviously subjected to greater strains in service than the other parts. For the purpose of strengthening this part of the shoe and of providing a body of fabric of increased thickness to 95 prevent the staples from tearing through the binder sheet when heavy strains are encountered, a toe reinforcing piece 13, formed of fabric coated on both sides with rubber, is employed. This piece is of a 100 size and shape corresponding with the toe portion of the binder sheet on which it is superposed. The staples 12 used to secure the toe portion of the binder sheet are driven through this piece. 105

The rubber outer sole 14 and heel 15, which may be formed integrally or separately as desired, are next cemented in place. They are made of sufficient size to extend to the extreme edge of the welt to give the de- 110

sired strength and body to the boot or shoe and the neat and attractive appearance characteristic of a leather shoe.

When the shoe has been built up as set

- 5 forth it is finally subjected to vulcanization whereby the parts are permanently vulcanized together. During vulcanization the outer sole and welt strip are so united as to become in effect an integral structure.
- 10 Therefore the staples 12 afford means by which the outsole near its margins is secured to the inner sole by permanent fasteners which are entirely concealed.

Shoes manufactured in accordance with 15 the invention are of attractive appearance and possess greater strength and wearing qualities than any of the other shoes of this character heretofore known.

Although one of the preferred embodiments of the invention has been described, it is to be understood that various modifications in the number, form, material and arrangement of the parts may be resorted to without departing from the spirit and scope 25 or sacrificing any of the advantages of the invention defined in the appended claims.

Having thus described my invention, what I claim and desire to protect by Letters Patent is:

30 1. A shoe comprising an insole, an upper having its lower margin turned over upon the insole, a vulcanized outer sole, and a vulcanized welt strip intermediate the insole and outsole, the said welt strip being secured to the insole by metallic fastening devices extending through the said margin of the upper.

2. A shoe comprising an insole, an upper having its lower margin turned over upon 40 the insole, a vulcanized outer sole, and a vulcanized welt strip intermediate the insole and outsole, the said welt strip being secured to the insole by metallic fastening devices extending through the margin of 45 the upper and being integrally united with the outsole by vulcanization.

3. A shoe comprising an insole, an upper having its lower margin folded over upon the insole, a vulcanized outer sole, and a vulcanized welt strip intermediate the insole and outsole and coextensive with the margin of the latter, the said welt strip being formed with a shoulder against which the upper rests at the line of fold of said margin, and being secured to the insole by metallic fastening devices extending through the margin of the upper.

4. A shoe comprising an insole, an upper having its lower margin turned over upon 60 the insole, a vulcanized outer sole, a vulcanized welt strip coextensive with the margin of the outsole, and formed with a tape-

like extension lying intermediate the soles, and concealed mechanical fastening means securing together said insole, margin and 65 extension.

5. A shoe comprising an insole, an upper having its lower margin turned over upon the insole, a vulcanized outer sole, a vulcanized welt strip coextensive with the margin of the outsole, and formed with an extension of reduced thickness lying intermediate the soles, said strip being secured to the insole by metallic fastening pieces extending through the margin of the upper. 75

6. A shoe comprising an insole, an upper having its lower margin turned over upon the insole, a vulcanized outer sole, a vulcanized welt strip coextensive with the margin of the outsole and formed with an extension of reduced thickness lying intermediate the soles, the said welt strip being secured to the insole by metallic fastening pieces extending through the margin of the upper, and being integrally united to the 85 outsole by vulcanization therewith.

7. A shoe comprising an upper and a bottom secured thereto, the said bottom comprising inner and outer soles, a welt strip and a binder piece intermediate said soles, 90 the outer sole, welt strip and binding piece being secured together by vulcanization, and metallic fasteners interengaging the welt strip, binder piece, and inner sole.

8. A rubber sole shoe comprising an inner 95 sole, an upper having a margin overlased on the inner sole and secured thereto, a welt strip overlapping the overlased margin of the upper, a binder piece secured to the inner sole both by vulcanization and by 100 metallic fasteners passing through the welt strip, a toe reinforcing piece, and an outer sole united to the welt strip and binder piece by vulcanization.

9. A rubber sole shoe comprising a fiber 105 board inner sole, a fabric upper having a margin overlased on the inner sole and secured thereto by metallic fasteners, a welt strip having an outer margin protruding beyond the sides of the upper and an inner 110 margin overlapping the overlased margin of the upper, a filler within the space bounded by the inner margin of the welt strip, a fabric binder piece secured in position by vulcanization, a fabric toe reinforcing piece united to the binder piece, metallic fasteners securing the toe reinforcing piece, binder piece and inner sole together, and an outer sole united to the binder piece and toe 115 reinforcing piece by vulcanization. 120

Signed at Williamsport, Pennsylvania, this 4th day of November, 1919.

LYMAN A. TRULL.
